[57] **CLAIM**

The ornamental design for a dispensing cap for liquid containers, substantially as shown and described.

DESCRIPTION

FIG. 1 is a perspective view of a dispensing cap for liquid containers, showing my new design;

FIG. 2 is a top plan view;

FIG. 3 is a front elevational view thereof;

FIG. 4 is a side elevational view thereof;

FIG. 5 is a rear elevational view thereof;

FIG. 6 is a bottom view thereof;

FIG. 7 is a perspective view thereof similar to FIG. 1, but showing the closure in an open position; and

FIG. 8 is a top plan view showing the closure in an open position.

Fig. 1.

Fig. 3.

Fig. 7.

*Fig. 2.**Fig. 3.**Fig. 4.**Fig. 5.**Fig. 6.*
